UNITED STATES PATENT OFFICE.

HARRY E. SHUMWAY, OF WATERFORD, NEW YORK, ASSIGNOR TO VAN ZANDT, JACOBS & CO., OF TROY, NEW YORK, A CORPORATION OF NEW YORK.

APPAREL-COLLAR.

1,088,631.

Specification of Letters Patent. Patented Feb. 24, 1914.

Application filed July 29, 1909. Serial No. 510,164.

To all whom it may concern:

Be it known that I, HARRY E. SHUMWAY, a citizen of the United States, residing at Waterford, county of Saratoga, and State 5 of New York, have invented certain new and useful Improvements in Apparel-Collars, of which the following is a specification.

The invention relates to such improvements and consists of the novel construction and 10 combination of parts hereinafter described and subsequently claimed.

Reference may be had to the accompanying drawings, and the reference characters marked thereon, which form a part of this 15 specification. Similar characters refer to similar parts in the several figures therein.

My invention relates to articles of wearing apparel which have been made comparatively stiff and rigid by laundry-starch or 20 other stiffening material, and more especially to turn-down or fold-collars.

The object of the invention is to facilitate the insertion of buttons in buttonholes rendered comparatively stiff and rigid by 25 laundry-starch or other stiffening material, as well as to improve the fit of the garment.

The invention consists in providing one 30 end of a collar-band or other portion of a garment with a buttonhole having comparatively stiff and rigid walls, in which a button secured to another portion of the garment can be easily and quickly inserted, as will be hereinafter more fully described and subsequently pointed out in the claim.

Figure 1 of the drawings is a front elevation 35 of a detachable turn-down collar detached, and showing the ends wholly separated from each other. A portion of each end of the collar-top is broken away to show the buttonholes in the ends of the band. Fig. 2 is a similar view, except that the ends 40 are brought together to the position assumed in use.

The collar is composed of the band, 1, 45 and the top or turn-down portion 2. One end, 3, of the band projects only a short distance from the neighboring end of the top, while the other end, 4, of the band projects a considerable distance from the neighboring 50 end of the top, and has its upper edge, 5, shaped to fit the fold, 6, when inserted therein between the band-end, 3, and the neighboring end of the collar-top. The

band-end, 3, is provided with a buttonhole, 8, located just back of the neighboring end 55 of the collar-top, as shown by solid lines in Fig. 1, and by dotted lines in Fig. 2, adapted to receive a collar-button or stud. The other end of the band is provided with a buttonhole, 9, located just back of the neighboring end of the collar-top, as shown by solid lines in Fig. 1, and by dotted lines in Fig. 2. This buttonhole is adapted to receive the button inserted in the buttonhole, 8, and thereby secure the ends of the collar 60 in the position shown in Fig. 2, wherein it will be seen that the ends of the collar-top nearly contact with each other, making it difficult to insert the collar-button in the buttonhole 9.

By having the buttonhole, 9, inclined as shown, it will not be necessary to lap the ends of the collar-band so great a distance in order to cause the whole of the button-head to pass the lower or forward end of the buttonhole, as it would if the buttonhole was not inclined to the median longitudinal line of the collar-band. Much less stress, therefore, is required to lap the ends of the collar-band sufficiently to insert the head of the 70 button in the buttonhole, 9, when the buttonhole is inclined as shown, which greatly facilitates the ease of inserting the button, and this is of great importance when the buttonholes are concealed beneath the ends of the 75 collar-tops, as shown, where they are not so easily accessible as would be the case if they were not covered. Furthermore, the inclination of the buttonhole, 9, causes that end of the collar-band to move upwardly when it 80 is released from the stress which caused the ends of the band to lap sufficiently to insert the button, for the reason that the upper inclined wall of the buttonhole slides along the shank of the button until the shank rests 85 in the extreme forward lower end of the buttonhole, thereby forcing the upper edge, 5, of the band against the fold, 6, on the other end of the collar, causing the parts to assume their proper and intended position 90 while in use, as shown in Fig. 2. It should be observed that the inclined buttonhole is closed and extends from the button-engaging end obliquely upward and backward beneath the collar-top, whereby the stress between the button and the buttonhole walls 95 100 105

tends to force the projecting end, 5, of the band up into the fold, 6, and maintain it there.

What I claim as new and desire to secure by Letters Patent is—

A turned down lock-front collar having the usual locking tab, said tab having a buttonhole provided with a slit extending downwardly and a recess located at the lower

end of the slit for the reception of the shank 10 of the collar button.

In testimony whereof, I have hereunto set my hand this 24 day of July, 1909.

HARRY E. SHUMWAY.
